[57] **CLAIM**

The ornamental design for a razor handle, as shown and described.

DESCRIPTION

FIG. 1 is a perspective view of a safety razor handle showing our new design as seen from the top, rear and left side; FIG. 2 is a perspective view thereof as seen from the bottom, rear and left side;

FIG. 3 is a top plan view thereof;

FIG. 4 is a bottom plan view thereof;

FIG. 5 is a right side elevational view thereof, the opposite left side being a mirror image of the side shown;

FIG. 6 is a longitudinal partial section view taken along the line 6—6 in FIG. 3;

FIG. 7 is a front elevational view thereof; and,

FIG. 8 is a rear elevational view thereof.
